Attorney, Agent, or Firm—Dallett Hoopes

[57] CLAIM

The ornamental design for a towel bar, substantially as
shown.

DESCRIPTION

FIG. 1 is a perspective view of a towel bar showing our
new design;

FIG. 2 is a top view, the bar being shown broken away
for ease of illustration;

FIG. 3 is a front view of FIG. 2;

FIG. 4 is a bottom view of FIG. 2;

FIG. 5 is an end view taken from the right of FIG. 1;

FIG. 6 is a sectional view taken on the line 6—6 of FIG.
3.
